UNITED STATES PATENT OFFICE.

LOUIS W. CHISM, OF SPRINGFIELD, MASSACHUSETTS.

MAIL RECEPTACLE.

Application filed February 25, 1922. Serial No. 539,065.

To all whom it may concern:

Be it known that I, LOUIS W. CHISM, a citizen of the United States, residing at Springfield, in the county of Hampden and State of Massachusetts, have invented certain new and useful Improvements in Mail Receptacles, of which the following is a specification.

This invention relates to mail delivery receptacles which have no permanent opening or covered slot, such as now commonly in use, for the insertion of mail matter, but instead are provided with normally locked doors to be opened by a master key carried by the postman and locked patron's doors to be opened by the respective individual keys of the individual patrons.

The objects in view are, to provide a receptacle having a postman's door and a patron's door and so constructed that it may be used either as a single unit by itself by the occupant of a single family dwelling, or may be used with a plurality of other duplicate units in combination and nested together therewith side by side in a battery or compartment arrangement for multiple family dwellings or apartment houses, office buildings and the like, in such combination and arrangement all of the postman's doors of the entire group or battery being so interconnected, by the nesting arrangement merely by bringing the receptacles into side wall engagement and without any supplemental parts or any need for modification or change, that all such postman's doors will move as one, so that the operation of a single postman's door lock will serve to lock or to release the postman's doors of the whole group or battery, which the construction is such, however, that no patron can have access to the interior of any receptacle or unit except his own; to provide a receptacle of such construction as will, whether the receptacle be used as a single unit or as one of a combined group or battery of units, prevent the insertion of prying blades, so that no leverage can be exerted against the flat front surface outwardly; to provide a receptacle that may be, and preferably will be, formed up out of sheet metal by easy and well known stamping and folding or forming operations, in order that such receptacles may be produced in great quantities with great strength and durability and be sold for a reasonable price; to provide means

for facilitating the work of distribution of the mail by the postman by so forming the postman's door that, when it is open, it will present an inclined chute or large tray with a large open upper side and end, in which a batch of mail matter, including papers, large size popular weeklies full length, other periodicals, small parcels and the like may be laid at one time, and this will be especially of aid when a large number of receptacles are used in a group, the doors 1 of the whole group being open at the same time and forming a series of distributing trays open and closely adjacent to each other; to provide a receptacle having a postman's door so mounted that on the release of the lock thereof such door will automatically swing open or swing down to inclined open position; to provide a construction such as will, while providing open top and side trays, eliminate sharp corners and sharp metal edges at places the postman is liable to strike his hands against in distributing and inserting the mail; to provide a construction of receptacle which may be treated with any suitable, preferably rust resistant, material; and to provide a receptacle of such form and outline as will readily lend itself to a great variety of forms of added ornamental features if desired by any particular patron.

When a number of receptacles or units are connected up in a single group, as above mentioned, for apartment houses or office buildings, all but one of the postman's doors, preferably that of the middle receptacle, will have their lock bolts or latches held in inoperative position, as by a pin, screw, stud, catch or by any other suitable means, and will have their key-holes either filled up or covered over, so that the postman will have but the one lock to operate for the group and will be able to determine at a glance the particular lock to be operated.

Of course the receptacles herein described and illustrated may be made of any suitable shape, and of any suitable material, preferably sheet metal, and weight of material, and will be made to conform to such requirements of the postal authorities governing such matters as are in force at the time of manufacture.

In the accompanying drawings:

Figure 1 represents a front elevation of a mail receptacle embodying my invention;

Figure 2, a longitudinal sectional view on the line 2-2 of Fig. 1, looking in the direction of the arrows;

Figure 3, a transverse sectional view on the line 3-3 of Fig. 1, looking in the direction of the arrows;

Figure 4, a longitudinal sectional view, at right angles to Fig. 2, through the lower portion of a central unit or receptacle and portions of other receptacles on each side thereof, to bring out graphically the relation of the parts and the interengagement of the journals or hinge-butts of the postman's doors when a plurality of receptacles are combined together in a single group or series;

Figure 5, a detail perspective view of one of the upper side corners of one of the receptacles, illustrating the dovetail construction for holding the sides 11 and top 12 of the back or casing 2 of said receptacle together, the construction of both of the upper corners thereof being the same;

Figure 6, an interior detail view of the journal or hinge-butt 32 of one receptacle nested in the bearing 37 and journal or hinge-butt 34 of an adjacent receptacle, the said journals or hinge-butts being interengaged;

Figure 7, a detail sectional fragmentary view on the line 7-7 of Fig. 6;

Figure 8, a detail sectional view through one end portion of the roll 9, rod 10 and the adjacent portion of the adjacent side 11 of casing or back 1, the other end of the rod 10 being similarly engaged with the other side 11 of said casing or back 1;

Figure 9, a fragmentary detail view to illustrate how all of the locks, but one, of the postman's doors of a group of receptacles or units when combined together, may be covered over; and

Figure 10, a fragmentary detail view illustrating, by way of example only, one way by which the bolts or latches of all of the locks, except one, of the postman's doors of a group of combined units or receptacles will be held inoperative.

Referring now in detail to the drawings, 1 designates the postman's door, 2 the back of casing, which may be mounted in place in any suitable manner as, for instance, by means of screws 3 passing through countersunk washers 4, through the back wall of casing or back 2 and into a suitable supporting medium or studding, not shown. These washers will serve to reinforce the material of said back wall of casing or back 2 to guard against tearing out around the screw perforations, thus preventing unauthorized removal by pilferers or thieves, and the washers 4 are countersunk, as best shown in Fig. 3, so that the heads of the screws will not project beyond the surface of said washers and so will not form abrupt pro-

jecting edges to catch mail matter, likewise, and for the same reason, the outer edges of the washers 4 are rounded off or beveled, as shown.

The door 1 has sides 5, preferably integral therewith, extending the full distance from the front of said door 1 to the interior face of back 2 or substantially thereto, the upper end edges of said sides 5 being rounded off at 6 as shown to permit the door 1 to swing outwardly in its bearings or around its pivotal point, and has its lower end 7 curved on an arc concentric with the axis of its hinge, the said lower end 7 fitting in, and engaging the inner face of the correspondingly shaped lower end portion 8 of the back or casing 1 and having sliding engagement therewith, the length and shape of said portions 7 and 8 being such that when the door 1 is in its extreme open position the edge of end portion 7 will lie flat against the adjacent portion of the inner face of portion 8 of back or casing 1 so as to guard against the end or edge of any envelope or paper lodging between these two portions and so possibly being overlooked or mutilated or interfering with the free movement of the door 1.

The edge of the lower portion 8 of back or casing 1 will preferably be rolled over, as at 9, to form a rest limiting the outward and downward movement of door 1 and supporting it when open and, if desired as a reinforcement, a rod 10 may be fitted into said roll. As a simple, economical and convenient method of construction this rod 10 may be extended through beveled holes in the adjacent portions of the sides 11 of the casing 2, the ends of said rod 10 being upset or spread in said holes; as illustrated in Fig. 8, and being flush with the outer lateral faces of said sides 11, so as to firmly secure the bottom portion 8 and sides 11 together while at the same time providing for reinforcing the roll 9 and avoiding lateral projections which might interfere with the nesting combination of the receptacles in a single group or battery of units.

The upper ends of the sides 11 may be connected with the top 12 of the back or casing 2 in any suitable manner, though they will preferably be interconnected with the top 12 by means of a dovetail form tongue 13 extending from, and preferably integral with, side 11, said tongue 13 being folded at right angles to the side 11 and pressed into a correspondingly shaped recess in the top 12, and a similarly formed tongue 14 extending from, and preferably integral with, top 12 and pressed into a correspondingly shaped recess in the upper portion of side 11, all as illustrated in Figure 5. This is a very strong and also very economical connection and may be easily made by folding over and pressing the tongues 13 and 14

14 into place during one of the stamping or folding operations with no need for a special operation or step for this especial purpose.

6 The postman's door 1 is provided with two small glass covered sight openings 15, through which the patron may quickly see if there is any mail in his receptacle, and a name slot or opening 16 behind which, and 10 closely adjacent thereto, is mounted a bracket 17 to receive a name card or strip. This opening 16 may be covered by glass if desired.

A large opening is formed in the door 1 15 to receive the patron's door 18, which is pivotally mounted in the door 1 by means of a pin 19 passing through hinge members 20 extending from one side portion of the door 18, and the intervening hinge member 21 extending from the edge of the corresponding and adjacent side wall of said 20 large opening. The material of the door 1 adjacent the edges of the ends and other side of said large opening is bent at right 25 angles toward the back or casing 2 to form a reinforcing and guard strip or rib 22.

The door 18 has its end portions and free side portion folded back upon itself to form a flat flange 23 lying flat against the adjacent portions of door 1 and extending well 30 beyond the walls of the large opening closed by said door 18, and also has the material of said portions extended and bent at right angles to said flange 23 toward the back or 35 casing 1 to form a reinforcing and guard strip or rib 24 extending around the end portions and free side of said door 18, said rib 24 lying closely adjacent to, or in contact with, the rib 22, the location and arrangement being such, however, that the portion of the rib 24 extending parallel to, and adjacent to, the free side of door 18 will 40 not bind against the corresponding portion of the rib 22 as the door 18 swings in opening or closing.

This rib 24 in addition to bracing the door 18 will also act as a stop to prevent the insertion of a prying blade, in a plane parallel with the door 1 and the door 18 between said doors and the ribs 24 and 22 being closely adjacent to each other will stiffen the material of the doors 1 and 18 at closely adjacent points and so will prevent and deformation which otherwise might permit a thin prying blade to be forced between the adjacent faces of these doors 1 and 18.

The top 12 has its front portion extended down slightly as at 25 substantially at right angles and then backward substantially at 60 right angles, as at 26, to form a channel reinforcement for this portion of the top 12, and the upper portion of the door 1 has its edge portion folded back toward the casing or back 1 substantially at right angles to 65 form a portion substantially parallel to the

portion 26 and then is given a large roll to form a tubular reinforcement 27 for the upper portion of the door 1, the adjacent faces of portions 26 and 27 lying so closely adjacent to each other as to prevent the insertion 70 of any bladed prying instrument of sufficient strength to have any value for such purpose.

The door 1 is provided with a suitable lock 28 suitably mounted upon the inner face of such door in such position that its bolt or latch will pass through a suitable opening or into a suitable socket in the rib or portion 26 midway of the ends thereof, a suitable key-hole 29 being provided for the operation of said lock 28 from the exterior of the receptacle by means of the postman's master key.

Similarly, a suitable lock 30 is mounted on the inner face of the patron's door 18 in such position that its bolt or latch will extend beyond the rib 24 and will be received in a suitable opening or socket in the rib 22 midway between the ends of the side of the large opening parallel to the pin 19, a suitable key-hole 31 being provided for the operation of said lock from the exterior of said receptacle by means of the particular patron's key.

In the construction illustrated by way of example the lower portions of the sides 5, 95 preferably integral with the door 1, are specially formed, one side being drawn out at such point to form a short cylindrical hollow small hinge boss or butt 32 of large diameter and having a closed end 33, the other side 5 of said door 1 being drawn in at such point to form a shorter hollow large hinge boss or butt 34 of a diameter larger than that of boss or butt 32 and of a length shorter than boss or butt 32, said boss or butt 34 having its inner end 35 closed, and the axes of said bosses or butts 32 and 34 being in alignment.

The hinge boss or butt 32 makes a snug fit in a large bearing 36 formed by cutting out a portion of the right hand side 11 of back or casing 2 and drawing out the material, or shaping it up, to form an annular flange extending substantially at right angles to the plane of side 11 and forming the walls of said opening, and the hinge boss or butt 34 is operatively mounted by means of an inwardly folded annular flange forming a bearing in the left hand side 11 of the back or casing 2, said bearing 37 having its inner 115 end open to permit free access to the closed end 35 of hinge boss or butt 34.

The diameter of the circle defined by the inner wall of bearing 37 is slightly greater than the diameter of the circle defined by the outer wall or face of bearing 36 in order that the exact duplicate of the bearing 36 and hinge-butt 32 of a duplicate receptacle will make a snug fit in the bearing 37, the relative lengths of the hinge-butts 32 and 130

34 being such that when two of the receptacles are arranged together as above with the bearing 36 and hinge-butt 32 of the one in the bearing 37 of the other, when said receptacles are forced together so that their adjacent sides 11 of their backs or casings 2 are in engagement, the adjacent faces of the closed end 33 of hinge-butt 32 and closed end 35 of hinge-butt 34 will be in, or substantially in, engagement with each other. This is not essential, but it is very desirable that the length of hinge butt 34 shall be such as to receive all that portion of bearing 36 and hinge-butt 32 which projects beyond the external face of its side 11 of the back or casing 2.

While it is preferred that the hinge-butts 32 and 34, with their closed ends 33 and 35 respectively, shall be formed integrally with the respective sides 5 of the door 1, as being easy of accomplishment in the usual well known sheet metal stamping, folding and associating operations, and as being a very strong, rigid, efficient and exceptionally economical construction lending itself to quantity production by machinery such as usually employed for this purpose, and although constituting important details of my invention, in its broader aspects such details might be substituted by separate hinge-butts bolted, riveted, welded or otherwise suitably secured in place in any convenient and well known manner, or might be substituted by other suitable means, and such construction would be within my invention as broadly envisioned, but such substitute construction as to this point would add to the number of operations to be performed in the construction of the receptacle and would add appreciably to the cost while decreasing the rate of production.

What has been said of the hinge-butts 32 and 34 as to the feasibility of their being substituted by other construction, for instance being separate parts suitably secured in position, applies also to the bearings 36 and 37.

The end 35 of hinge-butt 34 has a plurality of long thin lugs 38 extending at right angles from the outer face of said end 35 toward its respective side 11 of casing 2, these lugs 38 not being concentric with the axis of hinge-butt 34, but preferably extending in a straight line tangentially of the axis of said hinge-butt 34. These lugs 38 are preferably formed by stamping out the metal of said closed end 35 on three sides and then bending it on its connected side to a position at right angles to the face of said end 35. These lugs 38 are preferably three in number, spaced equi-distantly from, and about, the axis of hinge-butt 34 and are adapted, and intended, to snugly fit into, and project through, straight, tangential, registering slots in the closed end 33 of

hinge-butt 32 of an adjacent receptacle, which hinge-butt 32 is received in the bearing 37, as shown in Figure 4, when a series of these receptacles are arranged in combined group or battery relation.

70

These lugs 38 need not project from the face of end 35 so far as shown, it being sufficient if they project therefrom to such a degree as to fit into the slots of the adjacent end 33 of the hinge-butt 32 of the postman's door 1 of an adjacent receptacle so as to interlock the doors 1 of such receptacles, the object of having such lugs 38 and slots receiving them being to connect up, or interlock, the doors 1 so that all the doors 1 so interconnected may be opened or closed as a single door by a single movement on the part of the postman or mail carrier.

75

Of course the lugs 38 need not be integral with the ends 35, separate ribs, lugs or cleats might be welded or riveted thereto, likewise, instead of the slots in the ends 33 to receive the lugs 38, recessed parts adapted to receive said lugs 38 might be welded or riveted to the ends 33, but all this would very materially add to the expense, would involve risk of such parts coming loose, and would greatly cut down the possible rate of production.

80

It will be noted that the point of gravity of the door 1, and the door 18 carried thereby, lies in a plane well in front of the axial line passing through the hinge-butts 32 and 34 and that, therefore, as soon as the postman's lock 28 is released the door 1 will automatically drop open or swing open, rotating or moving about its axis by the action of gravity.

85

In assembling in a group or series, as illustrated in Figure 4, the receptacle A is arranged with its right hand side 11 of casing 2 in engagement with the left hand side 11 of casing 2 of receptacle B, the bearing 37 of which receives the bearing 36 and hinge-butt 32 of receptacle A, the end 33 of hinge-butt 32 of receptacle A receiving in its respective slots the respective lugs 38 extending from end 35 of hinge-butt 34 of receptacle B, which latter receptacle, B, has its right hand side 11 of its casing 2 in engagement with the left hand side 11 of casing 2 of receptacle C, with its bearing 36 and hinge-butt 32 nested in the bearing 37 and hinge-butt 34 of receptacle C, and with the lugs 38 of the end 34 of the hinge-butt 34 of receptacle C protruding into, or through, as shown, the respective cooperating slots in end 33 of hinge butt 32 of receptacle B, and this arrangement may be continued for a large number of receptacles.

100

The special point in having the lugs 38 and cooperating slots of the form and outline and relative sizes as shown and above described is to obtain a large bearing surface so that both side faces, as well as both

110

115

120

125

130

- end faces, of the lugs 38 will bear against the walls of the respective slots of the co-operating hinge-butts 32 in opening and closing the doors, instead of just the narrow 5 end edges which would rapidly wear out or cut under, reducing the size of the respective lugs 38 and increasing the length of the respective cooperating slots rapidly and so resulting in a large degree of lost motion 10 in the interengaging means of the doors 1 of a particular group of receptacles. Any suitable arrangement, other than that shown as well as that shown, which will result in the side faces of the lugs 38 being in operative engagement with the side walls of the cooperating slots would accomplish or substantially accomplish the object here in view and will be within the spirit of my invention. 15
- 20 Only the preferred form or construction has been shown and described and it will be obvious that many changes and modifications may be made while still remaining within the scope and spirit of my invention.
- 25 Having thus described my invention, what I claim as new and desire to secure by Letters Patent is:
1. A plurality of complete unitary receptacles adapted to be mounted in supported position in adjacency with their adjacent sides substantially in engagement to form a single group of combined receptacles, each said receptacles having a door swinging on an axis, the axes of said doors of all of said 30 receptacles being in alignment, the said door of each receptacle being provided with means for engaging with the said doors of the receptacles on either side of such receptacle so that the said doors of all of the 35 said receptacles, when arranged in combined relation, will all be connected together and move simultaneously to open or closed position.
  2. A plurality of mail delivery receptacles 40 adapted to be mounted in supported position in adjacency, a door journaled in each of said receptacles, and means for actuating the door of each receptacle by the door of one of the next adjacent receptacles.
  3. A plurality of mail delivery receptacles 45 adapted to be mounted in supported position in adjacency, a door pivotally mounted in each receptacle, and door actuating means carried by each door and adapted to cooperate with the door actuating means of the door of the next adjacent receptacle to cause simultaneous movement of the one door by the movement of the other door.
  4. A plurality of mail delivery receptacles 50 adapted to be mounted in supported position in adjacency, each of said receptacles comprising a door, each said door being provided on one side with an element which projects laterally to one side of the particular receptacle, and each said receptacle 55
- and its door being so formed at its other side as to receive the projecting element of the adjacent side portion of the immediately adjacent receptacle to couple said doors together for simultaneous movement. 70
5. A receptacle capable of use as a single unitary receptacle complete in itself or as one of the units of a series of combined units, said unit comprising a casing and a door having lateral portions, the respective sides of said casing being provided with openings to leave parts of the respective side portions of said door exposed therethrough in order that the doors of two adjacent receptacles may be connected to each other through said openings for movement as one in opening and closing. 75
6. A receptacle capable of use as a single unitary receptacle complete in itself or as one of the units of a series of combined units, 80 said unit comprising a casing having side portions formed with bearings, said bearings having their axes in alignment, in combination with a door having trunnions, one of said trunnions being received in one of said bearings, and the other trunnion receiving the other bearing, which is adapted to receive a portion of the adjacent trunnion of the door of an adjacent receptacle when said receptacle is used as one of the units 85 of a series of combined units, the respective side portions of said casing being provided with openings through which the doors of the immediately adjacent receptacles of a series of combined receptacles may be connected with each other for movement as a single element in opening and closing. 90
7. A receptacle comprising two members pivotally connected together adjacent the lower end of the receptacle and having overlapping side and end portions having sliding engagement with each other, one of said members constituting a movable part or large door, the other member being adapted to be permanently mounted and held in fixed position upon a suitable support, the upper end of said door and the upper portion of said stationary member being folded over toward the inner rear face of said stationary member and carried a substantial distance toward the same and being located with their adjacent faces very closely adjacent each other when said door is shut for the purpose of preventing the insertion of a prying blade between said members. 95
8. A mail receiving receptacle comprising a casing adapted to be permanently mounted upon a suitable support and having a back wall, top and sides, said sides having bearings adjacent their lower ends, in combination with a door having a front wall, side walls and curved bottom portion, the said side walls normally fitting between the sides of the casing and being provided with trunnions having their axes in alignment 100
- 105
- 110
- 115
- 120
- 125
- 130

- and received by the respective bearings above mentioned, said trunnions being so formed that when two or more duplicate receptacles are arranged in adjacency they may be so arranged that the trunnion of one side of the door of one receptacle will engage and interlock with the trunnion of the adjacent side of the door of the immediately adjacent receptacle, whereby when so arranged the doors of said receptacles will move simultaneously and to like degree in opening and closing.
9. A mail receiving receptacle comprising a casing adapted to be permanently fixedly mounted upon a suitable support and having a back wall, top, sides and arcuate bottom, said sides having bearings adjacent their lower ends, in combination with a door having a front wall, side walls and arcuate bottom portion, the said side walls of said door fitting between the sides of the casing and being provided with trunnions having their axes in alignment and received by the respective bearings above mentioned, said trunnions being so formed that when two or more duplicate receptacles are arranged in adjacency they may be so arranged that the trunnion of one side of the door of one receptacle will engage and interlock with the trunnion of the adjacent side of the door of the immediately adjacent receptacle, whereby, when so arranged, the doors of said receptacles will move simultaneously and to like degree in opening and closing, and the said arcuate bottom portions of the casing and door being concentric with the said trunnions and having a surface sliding engagement with each other.
10. A mail receiving receptacle comprising a casing adapted to be permanently fixedly mounted upon a suitable support and having a back wall, top, sides and bottom, said sides having bearings adjacent one end, in combination with a door having a front wall and side walls, the said side walls of said door fitting between the sides of the casing and being provided with trunnions having their axes in alignment and received by the respective bearings above mentioned, said trunnions being so formed that when two or more duplicate receptacles are arranged in adjacency they may be so arranged that the trunnion on one side of the door of one receptacle will engage and interlock with the trunnion of the adjacent side of the door of the immediately adjacent receptacle, whereby, when so arranged, the doors of said receptacles will move simultaneously and to like degree in opening and closing.
11. A mail receiving receptacle comprising a casing adapted to be permanently mounted upon a suitable support and having a back wall, top and sides, said sides having bearings adjacent their lower ends, in combination with a door normally locked and having a front wall, side walls and curved bottom portion, the said side walls of said door fitting between the sides of the casing and being provided with trunnions having their axes in alignment and received by the respective bearings above mentioned, said trunnions being so formed that when two or more duplicate receptacles are arranged in adjacency they may be so arranged that the trunnion of one side of the door of one receptacle will engage and interlock with the trunnion of the adjacent side of the door of the immediately adjacent receptacle, whereby, when so arranged, the doors of such receptacles will move simultaneously and to like degree in opening and closing, and means for limiting the outward movement of said door and supporting it in an inclined open position, wherein it presents a receiving tray with retaining sides and an open upper side and front end.
12. A mail receiving receptacle comprising a casing adapted to be permanently fixedly mounted upon a suitable support and having a back wall, top and sides, said sides having bearings adjacent their lower ends, in combination with a door having a front wall, sides and bottom, the said side walls of said door fitting between the sides of the casing and being provided with trunnions having their axes in alignment and received by the respective bearings above mentioned, the end portions of said trunnions being so formed that when two or more duplicate receptacles are arranged in adjacency they may be so arranged that the trunnion of one side of the door of one receptacle will engage and interlock with the trunnion of the adjacent side of the door of the immediately adjacent receptacle, whereby, when so arranged, the doors of such receptacles will move simultaneously and to like degree in opening and closing.
13. A receptacle comprising a sheet metal casing having side portions formed with laterally projecting open ended bearings drawn up therefrom, said bearings having their axes in alignment, one of said bearings protruding beyond the external face of its respective side portion and the other extending from the interior face of its respective side portion toward the other bearing, in combination with a door having trunnions, one of said trunnions being received in one of said bearings, and the other trunnion receiving the other bearing.
14. A receptacle comprising a casing having side portions provided with bearings, in combination with a metal door having integral trunnions fitting in and receiving the respective bearings, one of said trunnions protruding outwardly beyond the plane of the external face of the adjacent side portion of said casing and the other of said

trunnions having a recessed outer face receiving the other, and inwardly extending, bearing.

15. A receptacle comprising a casing having a large diameter open ended bearing extending toward, and in, the interior of said receptacle, and a smaller diameter open-ended bearing extending from the outer face of the opposite portion of the receptacle, 10 said bearings having their axes in alignment and the larger diameter bearing being of a size to snugly receive the smaller diameter bearing, in combination with a door having a cylindrical trunnion received in the 15 small diameter bearing and a cylindrical recessed trunnion of larger diameter receiving the larger diameter bearing, the smaller diameter trunnion being provided with protrusions and the larger diameter trunnion 20 being so formed that it may receive the said protrusions of the door of a duplicate receptacle if the latter be arranged in adjacency thereto with its smaller diameter trunnion and bearing fitting into the larger diameter 25 bearing and trunnion of said receptacle.

16. A receptacle comprising a casing having side portions provided with suitable open-ended bearings, in combination with a sheet metal door pivotally mounted in

said casing by means of trunnions integral 30 with said door and located in said bearings, one of said trunnions being provided with tangentially extending projections and the other of said trunnions being provided with registering tangentially extending sockets 35 equal in number to said projections and adapted to snugly receive the said projections of the first mentioned trunnion of a duplicate receptacle.

17. In combination, two receptacles each 40 comprising a casing having open-ended bearings and a door having trunnions mounted in said bearings, the trunnion on one side of one receptacle projecting beyond the external face of the casing thereof and having a closed end formed with projections, and the trunnion on the adjacent side of the other receptacle, and the bearing therefor, being formed to receive the above mentioned projecting trunnion and its bearing and being provided with means for snugly receiving the said projections whereby, the adjacent sides of the casings of said receptacles being substantially in engagement, the doors of said receptacles will be 50 interlocked for movement together as a single element.

LOUIS W. CHISM.
